UNITED STATES PATENT OFFICE.

GEORGE BICKELHAUPT, OF NEW YORK, N. Y.

FURNACE FOR HEATING SOLDERING-IRONS.

SPECIFICATION forming part of Letters Patent No. 637,198, dated November 14, 1899.

Application filed February 3, 1899. Serial No. 704,371. (No model.)

To all whom it may concern:

Be it known that I, GEORGE BICKELHAUPT, of the city of New York, borough of Manhattan, in the county and State of New York, have invented a new and Improved Furnace for Heating Soldering-Irons, of which the following is a full, clear, and exact description.

The invention relates to furnaces used by plumbers and other mechanics; and its object is to provide a new and improved furnace for heating soldering-irons and the like in a very simple and economical manner.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a longitudinal sectional elevation of the improvement on the line 1 1 in Fig. 2. Fig. 2 is a sectional plan view of the same on the line 2 2 in Fig. 1, and Fig. 3 is a transverse section of the same on the line 3 3 in Fig. 1.

The improved furnace for heating soldering-irons is provided with a portable casing A, preferably made of sheet metal and having legs A' and a fire-brick lining B in the upper portion, the front and bottom of the casing being open to permit of introducing the soldering-irons through the open front and to allow air to pass through the open bottom to a burner C. A burner C extends in a longitudinal direction in the casing below the fire-brick lining, as is plainly indicated in the drawings, and it consists of two longitudinal pipes C' and C'', connected with each other at their ends by cross-pipes C' C'', of which the pipe C' is supported in a suitable bracket D, attached to a cross-bar A' of the casing at the open front thereof. The rear cross-pipe C'' terminates in a longitudinally-extending pipe C'', supported in and extending through the rear end of the casing A, and in the bottom of this pipe C'' is formed a large air-inlet C''' for allowing air to pass into the pipe and mix with the gas supplied through a pipe E, connected with a suitable source of gas-supply and opening in a small jet into the extreme rear end of the pipe C'', as is plainly shown in Fig. 1. A

valve E' on the supply-pipe E serves to regulate the amount of gas allowed to pass into the pipe C'', and thus insures a proper mixing of gas and air. The longitudinal pipes C' and C'' are provided at their inner opposite sides with rows of apertures C' for the inflammable mixture of gas and air to pass through in small jets, said apertures being protected against scales or other small particles by overhanging projections or lugs C'', secured on said pipes. (See Fig. 3.)

Now it is evident that when the valve E' is opened a mixture of gas and air is formed in the pipe C'', and this mixture flows from said pipe, through the pipe C', into the longitudinal pipes C' C'' to issue from the same in small jets through the apertures C', and this mixture is ignited at the apertures to produce jets of flame for heating the irons supported above the burner on a pair of supports F, each made with two upwardly-curved arms F' F'', adapted to rest on the top of the pipes C' C'', respectively. The middle portions F''' of the arm-supports F are pivotally connected with downwardly-extending arms G, secured on a longitudinally-extending shaft H, mounted to turn and to slide in suitable bearings A''' A'', arranged on the casing.

The forward end of the shaft H projects somewhat at the front of the casing and is provided at its end with an arm I for turning said shaft to swing the arms G either to the right or to the left and move the arm-supports F from their normal central position (shown in full lines in Fig. 3) into a sidewise position, as indicated in dotted lines in Fig. 3, so that only one of the arms F' or F'' stands midway between the two pipes C' C'' to bring a soldering-iron supported on said curved arm directly over the jets of flame issuing from the pipes C' C''.

The arm-supports F can be locked in their normal position (shown in full lines in Fig. 3) by sliding the shaft H rearwardly to bring a key H' on said shaft in engagement with a corresponding aperture formed in the bearing A'', so that the shaft cannot be turned. (See Figs. 1 and 2.)

When it is desired to change the position of the arm-supports, the operator pulls the handle I outward and slides the shaft H in the same direction, so as to disengage the key

H' from the aperture in the bearing A' to permit of turning the shaft H, and thus bring either set of curved arms F' or F² between the burner-pipes C' and C².

5 The overhanging projections C³ are preferably provided with cut-out portions C⁹ (see Fig. 2) for the arms F' F² to pass into when moved into a middle position, as above explained.

10 Below the shaft H is arranged a pan J, removably supported on brackets carried by the legs A', said pan being adapted to receive any dross or scales or other matter falling off the soldering-irons placed on the supports F.

15 When the supports are in the position shown in Fig. 3, two soldering-irons can be placed on the two sets of curved arms F' and F² and heated by the jets of flame issuing from the pipes C' and C², as above explained, and when 20 it is desired to heat a single iron very quickly the operator shifts the shaft H, as previously explained, by unlocking the shaft from its bearing and swinging the arm I over to one side, by striking the arm with the soldering-iron, and then placing the soldering-iron into 25 the set of curved arms F' or F², extending between the pipes C' and C².

A furnace constructed in the manner described is portable and by means of a rubber 30 tube or the like can be connected by the pipe E with the gas-pipe in a building for supplying the necessary amount of gas for the inflammable mixture, as above explained.

The top of the casing A may be provided 35 with an outlet-opening K, as indicated in Fig. 1, so that when the cover of this opening is removed an increased draft is had for the burner.

Having thus fully described my invention,

I claim as new and desire to secure by Letters Patent—

1. A furnace, comprising a casing, a burner in the casing and consisting of a plurality of pipes, a support consisting of oppositely-extending arms, a shaft on which the support is mounted, the said shaft being adapted to rock in the casing, and means for locking the shaft to hold the support in a central position relatively to the burner, substantially as specified.

50 2. A furnace for heating soldering-irons, comprising a casing open at one end and at the bottom, a burner arranged in said casing and formed of a plurality of apertured pipes connected with a mixing-pipe having an air-inlet and a gas-inlet, a pair of supports each in the form of two curved arms adapted to rest on said apertured pipes, arms for the supports, and a shaft mounted to turn and to carry said arms, substantially as shown and described.

55 3. A furnace for heating soldering-irons, comprising a casing open at one end and at the bottom, a burner arranged in said casing and formed of a plurality of apertured pipes 65 connected with a mixing-pipe having an air-inlet and a gas-inlet, a pair of supports each in the form of two curved arms adapted to rest on said apertured pipes, arms for the supports, a shaft mounted to turn and to carry said arms, and means, substantially as described, for locking said shaft against rotation, as set forth.

GEORGE BICKELHAUPT.
